UNITED STATES PATENT OFFICE.

RUDOLPH H. FENKHAUSEN, OF SAN FRANCISCO, CALIFORNIA.

ELECTRIC SWITCH.

1,070,674.

Specification of Letters Patent. Patented Aug. 19, 1913.

Application filed September 4, 1912. Serial No. 718,452.

To all whom it may concern:

Be it known that I, RUDOLPH H. FENKHAUSEN, a citizen of the United States, and resident of the city and county of San Francisco, State of California, have invented a new and useful Electric Switch, of which the following is a specification.

This invention relates to a novel combination of a starting device for electric motors and the like, having reference particularly to alternating current motors, and comprises more particularly a novel knife-switch mechanism for controlling the current to the main-line conductors, and has for an object 10 to provide a switch-mechanism, which is normally locked in neutral position against movement from this position to the running contact position.

It has for a further object to provide a 20 simple and effective means for protecting the motor during the starting operation and which, according to the novel features of my invention, must be thrown into operation before the switch can be shifted to its running position, thereby eliminating the danger incident to throwing the switch through inadvertence or mistake from the neutral position to the running position.

In starting devices heretofore used in 30 practice, it has been generally necessary to employ a compensator for use during the starting operation of a motor, and a further object of my invention is to provide a mechanism which dispenses with the use of 35 a compensator or like device and which serves the same purpose of protecting the main line machines from a too heavy current during the starting operation.

To the above ends, my invention consists 40 of a double throw switch, adapted to move from neutral to starting and running position and provided with means to automatically throw said switch from starting position to running position at a predetermined 45 time.

It also consists of a novel construction of a double throw switch having two sets of fuses provided with suitable connections, one set of fuses being adapted for higher am- 50 perage than the other.

It also consists of a novel construction of a double throw switch having two sets of fuses having suitable connections, one of

said sets being adapted for higher amperage than the other, and means to lock said switch 55 in neutral position to prevent movement of said switch in one direction.

It further consists of other novel features of construction, all as will be hereinafter 60 fully set forth.

For the purpose of illustrating my invention I have shown in the accompanying drawings a preferred embodiment which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a transverse section of a double throw switch and its adjuncts 75 comprising my invention. Fig. 2 represents a section on line $x-x$, Fig. 1. Fig. 3 represents on a reduced scale a section on line $y-y$ of Fig. 1. Fig. 4 represents an elevation of the inner side of the cover plate of 80 the switch casing showing my novel switch locking mechanism. Fig. 5 represents a detail of one section of the switch casing showing the preferred type of attaching means therefor. Fig. 6 represents a section of a 85 portion of the device showing certain details of construction. Fig. 7 represents a perspective view partly in section showing the position the parts assume when moving.

Similar numerals of reference indicate 90 corresponding parts in the figures.

Referring to the drawings:—1 designates the casing for the switch and its adjuncts, which in the present instance is formed in sections in order to permit easy access to 95 any of the parts contained therein. As here shown there is preferably a rear plate 2, to which is fixedly secured the top and bottom plates, 3 and 4, while the side plates 5, are each detachably connected to the rear plate 2, as is also the front plate or cover 6. As a means for readily permitting removal 100 of the side plates 5, I preferably provide a plurality of openings, 7, with which dowel members, 8, forming a part of the sides, 5, 105 are respectively adapted to engage. This

construction correctly locates and retains the said side plates relative to the remaining sections of the casing, and they are furthermore locked and held against displacement by providing slots, 9, in one edge of each, which slots are adapted to straddle screws, 10, which pass through the front plate 6 and into partitions 11. It will thus be apparent that by loosening the said screws, the side members can slide out and be removed entirely, by withdrawing the dowels 8 from the rear plate 2. The interior portion of the casing is preferably lined with asbestos 12, or like material, for a purpose readily apparent.

The partition members 11 pass transversely at spaced intervals from one side of the casing to the other, being secured by screws, 13 or the like, to the rear plate 2, and thus divide the casing into three compartments which are designated by the reference numerals 14, 15 and 16. Attention is directed to the fact that these partitions 11 are preferably of non-conducting or insulating material and serve as supports for certain of the contact and conducting elements of the switch and its accessories.

17 designates a base-block, preferably of insulating material, which is suitably secured to the plate 2, by means of screws, 18, or the like, and forms a support for the switch lever, 19. This lever, in the present instance, is a conventional type of knife switch, having in the present instance three contact blades 20, each of which is pivotally connected or mounted between the bifurcated ends of a contact plate 21. These plates 21 are preferably of copper to form a suitable conductor for the current, and are electrically connected to the said blades 20 by means of bolts 22, as will be apparent. The blades 20 have their outer ends, as is customary, joined to a bar 23 of insulating material, and to this bar the switch handle, 24, is connected, the connection in the present instance comprising a pair of threaded rods, 25, secured at one end to the bar 23 and at the opposite end by means of nuts, 26, to the strip 27.

50 The line wires 28, of which in the present case there are three, are led through a suitable fitting, 29, of porcelain or the like insulating material, each wire of course passing through a separate opening, and being soldered or otherwise united to its respective plate 21.

30 designates a set or gang of spring contacts carried by one of the partitions 11 and each of which is located in the path of movement of one of the switch lever blades 20 and it will of course be understood, that, as customary, these spring contacts are provided with a bifurcated end, 31, adapted to receive the blade 20 and form a good

electrical contact therewith, the said ends being so adjusted as to require a spreading action when the blade is seated therein. This action of course creates a tension which insures the desired contact. In order to guide the blades 20 into their respective contact, the bifurcated portions of each clip are outwardly flared as shown at 32, thus insuring a proper contact even though the clips may have become slightly bent out of proper alignment.

33 designates substantially U-shaped spring-sockets, secured to the partitions 11 by means of screws, 34, or the like, and which also serve to connect the clips 30 to the same partition, thereby affording electrical connection between the two members on opposite sides of the said partition. In the present instance there is one of these sockets for each clip 30 and each serves to support in a detachable manner one end of a fuse, 35, the opposite end of which is likewise supported in spring sockets, 36, of similar design, which are connected through the partition 11 with bolts and nuts, 37. It will thus be apparent that the compartment 15 serves as a receptacle for a plurality of fuses which can readily be reached by sliding out the side plate 5, as already explained. The compartment 16 also contains a plurality of fuses, 38, which, in the present instance, are similarly mounted in sockets connected respectively to clips and nuts and as the construction of these elements is exactly similar to that described for the opposite side of the casing, the same reference numerals will be applied thereto. There is of course a difference, as regards the electrical connections for the nuts 39, since they are respectively connected by conductors, 40, with the nuts 37 and each has a line wire, 41, electrically united thereto and passing through the fitting 29 to the point of use.

42 designates a spring suitably secured at one end to a fixed portion of the device, and having its free end in alignment with one of the blades 20 of the switch member 19, and the neutral position of this lever is shown in Fig. 2. The spring 42 preferably rests against the blade without exerting any pressure thereon. If, however, the switch member is moved to the right, as shown in Fig. 2, to the starting position, the spring immediately comes into action tending to throw the lever out of contact and return it to neutral position, so therefore it is necessary to manually hold the lever in its starting position.

43 designates a lock or latch member suitably pivoted at 44 to the cover 6, and provided with a latch finger, 45, adjacent which a cam face, 46, is located, and it will be noted that in operative position the cam face 46

is disposed between the latch 45 and the starting side of the switch mechanism. The end of this lock 43 preferably works in a guide, 46', which always maintains said member in proper relation to the parts which it controls.

It will of course be understood that the lever handle 24 projects on the outside of the casing in order that the knife-switch may 10 be properly operated, and I therefore provide a pair of slots, 47, in the cover 6, through which the rods 25 are adapted to pass and within which they may slide from one position to another. It is with one of these rods 15 25 that the latch 45 co-operates and it will be seen that when the lever is in neutral position it cannot be moved toward the running side of the switch without first moving it to the starting side. When once at the 20 starting side, it can be shifted to the running side by quick movement which causes the rod 25 to strike the cam surface 46 and raises the latch 45 temporarily out of its path, and, before the latch drops back to its 25 normal position, the rod and switch lever has passed out of the line of travel of the latch.

Attention is now directed to an important fact relative to the two sets of fuses 35 and 30 38, and that is, that the former 35 on the starting side of the switch are adapted for a much higher amperage than those on the running side or 38, since these latter are only of sufficient amperage to give adequate 35 current on the running side. The reasons for this construction will be readily apparent when it is stated that it is common and general practice to utilize, in connection with a three pole switch, but one set of fuses, 40 namely those of low amperage for the running current while the starting current is taken care of by a rheostat or compensator, which is thrown into the circuit until the line has come up to load and then it is 45 thrown out and the fuses protect the line. In my present invention I have devised a switch mechanism which does not require the use of a compensator or other apparatus of a like nature, but instead, a second set of 50 fuses of higher amperage is employed during the starting operation.

In normal position of the switch, with no current flowing to the line, the knife switch-lever 19 is in neutral position as shown in 55 full line Figs. 1 and 2 and in this position it is securely locked by the latch 45 against movement toward the running side of the device. When it is desired to close the circuit and throw the current into the line, the 60 knife-switch member is manually shifted to the starting side, thus bringing the blades 20 into contact with the spring contacts 31, and throwing the current into the line through the large fuses 35. In this position the op-

erator holds the switch member against the 65 tension of the spring 42, for a length of time sufficient to bring the line up to load, and to normal running condition, after which the lever is relieved and the spring 42 kicks or throws the lever over to the running side 70 into engagement with the spring contacts 31 on that side, and diverts the current through the small running fuses 38. The latch-member 42 is rendered inoperative during this movement owing to the fact that the rods 25 75 of the switch member strike the cam 46 and throw the latch 45 out of the path of movement of the switch member, which latter traverses the space so quickly, that it has assumed a running position before the latch 80 45 drops back to its normal position.

It will now be apparent that I have devised a complete unitary structure, simple in construction and effective in use and embodying a compact inclosing casing for its 85 adjuncts comprising features which leave no live metal or wires exposed and furthermore which is locked in neutral position and cannot, therefore, be accidentally or inadvertently shifted to running position, said locking mechanism being only released after a movement to the starting position. It further comprises a plurality of compartments independent of each other and of the main switch compartment, each of which is readily accessible for the replacement of fuses without opening the main compartment or without opening but the one compartment in which the fuses to be replaced are located. 90

It will be seen that the lever 25 swings in 100 a plane at a right angle to that in which the latch 43 swings, and the latch 43 lies transversely across the lever. The lever 25 is spring actuated, while the latch 43 is gravity actuated. Therefore the lever 25 may move 105 in horizontal plane while the latch 43 may move in a vertical plane. The advantage of this arrangement, is that the movement of the lever more positively pushes the latch away from its path of movement as it crosses 110 the neutral position. At the same time a simple structure is effected.

Having thus described my invention, what I claim as new and desire to secure by Letters Patent is:—

1. In a device of the character described, an outer casing, spaced terminals therein, a spring-pressed lever pivotally mounted and adapted to engage said terminals, a gravity latch located within said casing and pivotally mounted and engageable with said lever to hold the same in a neutral position between said terminals, said lever and latch being arranged to swing in planes approximately at a right angle to each other, and a support for the free end of said latch, whereby the latter is normally retained in proper relation to said lever. 115 120 125

2. In a device of the character stated, the combination of a casing, a double throw switch pivoted in said casing, a lever secured to said switch and projecting exteriorly of said casing, a cover for said casing having a slot therein serving as a guide for said lever, a plurality of sets of fuses located on opposite sides of said switch and having suitable connections, one of said sets of fuses being adapted for higher amperage than the other, a latch located within said casing for preventing movement of said switch in one direction, means operated by the movement of said switch from starting to running position to release said latch after said switch has first been moved to starting position, and an elastic medium located in the starting path of movement of said switch within said casing and adapted to throw said switch to running position.
3. In a device of the character stated, the combination of a casing, a double throw switch pivoted in said casing, a lever secured to said switch and projecting exteriorly of said casing, a cover for said casing having a slot therein serving as a guide for said lever, a plurality of sets of fuses located on opposite sides of said switch and having suitable connections, one of said sets of fuses being adapted for higher amperage than the other, a latch located within said casing for preventing movement of said switch, in one direction, in inoperative position of said switch, means operated by the movement of said switch from starting to running position to release said latch, after said switch has first been moved to starting position, and a tension device located in the starting path of movement of said switch and adapted to be placed under tension by contact with said switch whereby said switch is automatically thrown to running position when released.
4. In a device of the character stated, the combination of a casing, a double throw switch pivoted in said casing, a lever secured to said switch and projecting exteriorly of said casing, a cover for said casing having a slot therein serving as a guide for said lever, a plurality of sets of fuses located on opposite sides of said switch and having suitable connections, one of said sets of fuses being adapted for higher amperage than the other, a latch located in said casing for preventing movement of said switch in one direction, in inoperative position of said switch, means operated by the movement of said switch to running position to release said latch after said switch has first been moved to starting position, and a spring having one end secured to a fixed point and its free end extending into the starting path of movement of said switch and adapted to be placed under tension by contact with said switch, whereby said switch is automatically thrown to running position when released.
5. In a device of the character stated, the combination of a casing, a double throw switch pivotally mounted in said casing for lateral movement, a pair of rods fixedly secured to said switch and projecting exteriorly of said casing, an operating member carried by said rods, a cover for said casing having a plurality of slots therein, each slot serving as a guide for one of said rods, a plurality of sets of fuses located on opposite sides of said switch and having suitable connections, one of said sets of fuses being adapted for higher amperage than the other, a pivotally mounted latch contained within said casing and intermediately of said sets of fuses for preventing movement of said switch in one direction, in inoperative position of said switch, means operated by the movement of said switch to running position to release said latch after said switch has first been moved to starting position, and an elastic medium located in the starting path of movement of said switch and adapted to throw said switch to running position.
6. In a device of the character stated, the combination of a casing, a double throw switch pivotally mounted in said casing for lateral movement, a pair of rods secured to said switch and projecting exteriorly of said casing, an operating member carried by said rods, a cover for said casing having a plurality of slots therein, each slot serving as a guide for one of said rods, a plurality of sets of fuses having suitable connections, one of said sets of fuses being adapted for higher amperage than the other, a pivotally mounted latch contained within said casing for preventing movement of said switch, in one direction, in inoperative position of said switch, means operated by the movement of said switch to running position to release said latch after said switch has first been moved to starting position, and a spring located in the starting path of movement of said switch and adapted to be placed under tension by contact with said switch, whereby said switch is automatically thrown to running position when released.
7. In a device of the character stated, a casing, a plurality of sets of fuses of different amperages supported within said casing, a double throw switch pivotally mounted intermediately of said sets of fuses, said switch having a rod 25 projecting therefrom to the exterior of said casing, a front plate 6 having a slot therein through which said rod passes, a latch 43 having one end pivoted to the interior of said plate and its other end supported so that said latch lies normally in a substantially horizontal line,

a cam face 46 on the under side of said latch, and a latch finger 45 intermediate said cam face and the free end of said latch, the latter coöperating with said switch rod to hold it normally in an intermediate position, but ineffective when the switch is thrown from the starting to the running position, said switch being free from restraint when so moving.
